APPARATUS FOR REFINING PAPER STOCK

Edwin Cowles, Cayuga, N. Y., assignor to The Cowles Company, Princeton, N. J., a corporation of New Jersey

Application May 9, 1941, Serial No. 392,611

8 Claims. (Cl. 92—23)

This invention relates to apparatus for refining paper stock and constitutes an improvement in apparatus of the type previously disclosed in my Letters Patent No. 2,033,123, No. 2,180,080, No. 2,218,449 and No. 2,220,676.

It is an object of the invention to improve the performance of such machines, particularly with respect to the separation of trash, dirt and undefibered material from clean fibrous material.

Other objects and advantages of the invention will appear hereinafter.

A preferred embodiment of the invention selected for purposes of illustration is shown in the accompanying drawings, in which,

Figure 1 is a top plan view of the machine.

Figure 2 is a side elevation.

Figure 3 is a vertical section through the base, impeller housing and bearing member, the impeller being shown in elevation.

Figure 4 is a similar view, showing the impeller also in section.

Figure 5 is a fragmentary perspective view of part of the impeller.

Figure 6 is a section on the line 6—6 of Figure 4, and

Figure 7 is a section on the line 7—7 of Figure 4.

The machine as illustrated generally in Figures 1 and 2 is of the vertical type, i. e. the main shaft rotates on a vertical axis as hereinafter described. A base 1 rests on any suitable foundation and may be secured thereto in any suitable manner. Immediately above the base 1 is an annular impeller housing 2, and above the impeller housing is a bearing member 3 for the lower end of the main shaft 4. Above the bearing member 3 is a shaft housing 5, and above the shaft housing is a gear housing 6. A horizontal motor 7 is supported on the gear housing to drive a horizontal shaft 8 through belt 9, the shaft 8 and shaft 4 being provided with suitable reduction gears to provide for rotation of shaft 4 at the desired speed.

The base 1 and bearing member 3, in addition to serving their functions as base and shaft bearing, respectively, also serve as end closure members for the impeller housing 2, and the three members constitute a casing for the working parts of the machine. Furthermore, the base 1 is provided with an annular chamber 11 for screened material, while the bearing member 3 is provided with a similar annular chamber 12, also for screened material. Chamber 11 is provided with an outlet opening 13 and chamber 12 is provided with a similar outlet opening 14, 55

through which openings screened material may be discharged from the machine.

Mounted on the lower end of shaft 4 for rotation within the impeller housing 2 are two substantially similar impeller members 16 and 17 in the form of discs having hubs 18 and 19 surrounding the end of the shaft and secured thereto by bolt 20. The hubs are of sufficient thickness to provide a substantially unobstructed space 21 between the impeller disks as shown in Figures 3 and 4 for purposes hereinafter described.

Mounted on the upper surface of the impeller member 16 at suitable intervals are a plurality of screen scraper members 22 and similar scraper members are mounted on the lower surface of the impeller member 17. The said scraper members may be of any desired design and may be mounted on the impeller in any desired manner. As illustrated herein, the said scrapers are secured to the impeller by bolts 24 and are made of flexible material so that the scraping edges may bear against the screens hereinafter described. The impeller members are also each provided with an annular rim or flange 25 around its outer periphery, but this rim is broken as indicated at 26 (Figures 5 and 7) adjacent the scraper members to provide outlet passages for the screen tailings, i. e. the rejected material which fails to pass through the screens and is scraped therefrom by the scraper members.

The upper and lower impeller members are also each provided with a set of impeller vanes 28 mounted on their upper and lower surfaces, respectively, for a purpose hereinafter described. Furthermore, the outer surface of the rim 25 of each of the impeller members may be provided with a multiplicity of recesses 29 for a purpose hereinafter described.

Two perforated screens 31 of similar construction are employed to cooperate with the upper and lower impeller members, the said screens being in the form of annular discs. The upper screen covers the annular chamber 12, and the lower screen covers the chamber 11, the arrangement of the screen mountings being such that in each case the material in the impeller chamber cannot enter the chambers 11 and 12 without passing through the screen perforations. Thus, the inner and outer peripheral edges of the screens are sealed between opposed rings 32, 33, 34 and 35 which, in turn, are seated and sealed in the base and bearing member, respectively. Cross bars 36 extend transversely between the rings 32 and 33, and these, together with the con-

neeted spaced annular rings 37 form a grid which supports the screen from the rear, leaving the front face clear for scraping action by the scrapers 22.

The impeller members 16 and 17 are spaced from the screens to provide screening chambers 41, and are provided with a plurality of slots 40 which afford communication between the space 21 and the screening chambers 41 where the active screening operation takes place, the screening chambers being otherwise separated from the space 21 by the impeller members. The upper impeller member 16 is also provided with slots 42 close to the hub 18 which afford communication between the space 21 and an outlet passage 43 formed in the member 3. It will be understood that the passage 43 is entirely separated from and has no communication with the annular chamber 12.

The impeller housing 2 is provided with three separate annular chambers, the chamber 46 being located opposite the space 21 and in direct and open communication therewith, and the chambers 47 and 48 being located opposite the rims of the impeller members 16 and 17, respectively, and in communication with the outlet passages 26 in said rims. The chamber 46 is provided with an inlet passage 49 arranged substantially tangentially to the said chamber in the manner and for the purposes set forth in my prior Patent No. 2,220,676. The chamber 46 is also provided with an outlet opening 51 communicating with the passage 52 in the manifold 53. Likewise, the chambers 47 and 48 are provided with outlet openings communicating with passages 54 and 55, respectively, in the manifold 53.

The operation of the apparatus may now be described. As previously described in Patent No. 2,220,676, the stock to be treated is introduced through the inlet opening 49 at relatively high velocity, i. e. 1500 lineal feet per minute or more, and at the same time the impeller members 16 and 17 are rotated to cause the rim velocities to approximate the velocity of the inflowing stock. It will be apparent, therefore, that the stock whirling in the chamber 46 and space 21 is subjected to a relatively intense centrifugal separating action, so that heavy constituents, such as particles of sand, metal, glass and the like tend to move outwardly toward the periphery of the chamber 46, where they may find their way into the passage 52 through which they may be discharged from the machine. On the other hand, light constituents such as bits of wood, rubber, cork and the like tend to move inwardly toward the hubs, where they may find their way into the slots 42 and thence to the passage 43 through which they may be discharged from the machine. Since the space 21 is substantially unobstructed, being devoid of vanes or other members tending to create turbulence, eddies and the like, the centrifugal separating action is very effective.

At the same time, stock moves from the space 21, through the slots 40 to the screening chambers 41, but it will be noted that since the stock makes a complete reversal of direction, i. e. through 180°, in entering the screening chambers, it is very difficult for any light constituents to enter the screening chambers, as they tend to continue on their path toward the slots 42. Consequently, as a result of the centrifugal action described, the stock which enters the screening chambers is already separated from much undesirable waste or trash material, and an improved screening result is obtained thereby.

The screening action obtained in the screening chamber is similar to that described in my prior patents before referred to, but a novel feature of the present apparatus is the discharge of the screen tailings through the passage 26 into the chambers 47 and 48, and thence into passages 54 and 55 for discharge from the machine. In the machines disclosed in my prior patents, the screen tailings were returned to and remain in the impeller chamber until removed through an outlet opening therefrom.

The vanes 28 serve not only to feed stock into the screening chambers 41, but also serve to maintain a pressure therein which is slightly greater than the pressure in the space 21 and chamber 46, and in the operation of the machine the speed of rotation of the impeller is so adjusted as to cause such greater pressure to be maintained therein. The recesses 29 in the periphery of the impeller members likewise tend to maintain a pressure in the chambers 41 and 48 which is slightly greater than the pressure in the space 21 and chamber 46. Consequently any flow of stock through the space between the rims of the impellers and the walls of the member 2 proceeds from the screening chambers to the space 21 and chamber 46 rather than in the reverse direction. This insures that all stock entering the screening chambers shall have first been subjected to centrifugal separating action, and also prevents good fibrous material from being lost by passing to the outlet passages 54 and 55 without first being subjected to screening action.

The combination of centrifugal separating action with a screening action and a separation of the screening chambers from the chamber wherein the centrifugal action takes place, whereby only centrifugally treated material is admitted to the screening chambers, together with the direct removal of screen tailings from the screening chambers, results in the production of remarkably clean defibered stock, which, of course, is delivered from the machine through the outlet openings 13 and 14.

It will be understood that the invention may be variously modified and embodied within the scope of the subjoined claims.

I claim as my invention:

1. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, and said impeller disk being provided with a passage near the hub through which stock may flow from said impeller chamber to said screening chamber.

2. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, a series of vanes mounted on said im-

steller in said screening chamber, and said impeller being provided with a passage near the hub through which stock may flow from said impeller chamber to said screening chamber.

3. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, scrapers mounted on said impeller in said screening chamber and bearing against said screen, and said impeller being provided with a passage near the hub through which stock may flow from said impeller chamber to said screening chamber.

4. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, a series of vanes mounted on said impeller in said screening chamber, scrapers mounted on said impeller in said screening chamber, and said impeller being provided with a passage near the hub through which stock may flow from said impeller chamber to said screening chamber.

5. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, said impeller disk being provided with a passage near the hub through which stock may flow from said impeller chamber to said screening chamber, and said impeller being provided with a passage through which screen tailings may be removed from said screening chamber.

6. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk

extending outwardly from the hub of said impeller to the outer periphery of said screen and separating said chamber from said screen but being spaced from said screen to provide a screening chamber, said impeller disk being provided with a passage near the hub through which stock may flow from said impeller chamber to said screening chamber, said impeller having a rim provided with a passage through which screen tailings may be removed from said screening chamber, and said casing being provided with a chamber opposite said passage to receive said screen tailings, said last named chamber being separated from said impeller chamber.

7. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, a series of vanes mounted on said impeller in said screening chamber, scrapers mounted on said impeller in said screening chamber, said impeller being provided with a passage near the hub through which stock may flow from said impeller chamber to said screening chamber, said impeller having a rim provided with a passage through which screen tailings may be removed from said screening chamber, and said casing being provided with a chamber opposite said passage to receive said screen tailings, said last named chamber being separated from said impeller chamber.

8. Apparatus for refining paper stock, comprising, in combination, a casing, a flat, annular screen in said casing, said casing having inlet and outlet openings on opposite sides of said screen, said casing having an impeller chamber, an impeller mounted for rotation in said chamber, said impeller being in the form of a disk extending outwardly from the hub of said impeller to the outer periphery of said screen and separating said chamber from said screen but being spaced from said screen to provide a screening chamber, said impeller disk being provided with a passage near the hub through which stock may flow from said impeller chamber to said screening chamber, said impeller chamber having an open, substantially unobstructed space therein wherein the stock is subjected to centrifugal separating action, said impeller chamber having a peripheral outlet opening for the discharge of heavy waste material, and said impeller disk having an additional passage near the hub for the discharge of light waste material.

EDWIN COWLES.
